PROCESS FOR ACETYLENE PRODUCTION
Robert S. Puistonen, New Canaan, Conn., assignor to
Chemical Construction Corporation, New York, N.Y.,
a corporation of DelawareFiled Apr. 1, 1965, Ser. No. 444,575
17 Claims. (Cl. 260—679)**ABSTRACT OF THE DISCLOSURE**

An improvement is provided in acetylene processes in which the hot acetylene-containing gas stream is quenched with heavy aromatic quench oil. The quench oil accumulates solid carbon particles which are removed from the gas stream during the quench step, and at least a portion of the quench oil is treated to remove entrained solid carbon particles. The quench oil portion is mixed with a stream of light hydrocarbon oil such as benzene, a benzene derivative such as xylene, or a light paraffinic oil such as hexane, which has a low boiling point relative to the heavy aromatic quench oil. A homogeneous mixture of heavy aromatic and light aromatic or paraffinic oils containing solid carbon particles is produced. This homogeneous mixture is then separated into a solid carbon phase free of aromatic oils and an aromatic or aromatic-paraffinic oils mixture free of solid carbon particles by filtration or centrifuging. The aromatic or aromatic-paraffinic oils mixture is then heated and distilled, to vaporize the light aromatic or paraffinic oil. The residual liquid aromatic oil phase consisting of heavy aromatic oil is then recycled. The vaporization of light oil from the oils mixture is preferably carried out during processing of the main process gas stream to remove residual heavy aromatic oil vapor. The gas stream is scrubbed and refluxed with light aromatic or paraffinic oil, to condense the heavy aromatic oil into a liquid phase with concomitant vaporization of the light aromatic or paraffinic oil into the gas stream. The liquid phase oils mixture produced after separation of solid carbon particles, and consisting of heavy aromatic oil together with light aromatic or paraffinic oil, is added to the light aromatic or paraffinic oil during the gas scrubbing and reflux step. The light aromatic or paraffinic oil component of the oils mixture is vaporized into the gas stream, while the heavy aromatic oil component of the oils mixture combines with the heavy aromatic oil liquid condensed from the gas stream and is subsequently recycled, to the initial gas quench step.

The present invention relates to the production of acetylene, and particularly relates to the removal of solid carbon particles from the quench oil employed in the production of acetylene. An improved sequence and method are provided, whereby the solid carbon particles are completely separated from the quench oil without loss of quench oil due to thermal degradation or inclusion in the separated solid carbon particles.

The production of acetylene generally involves the reaction of a fluid hydrocarbon such as methane or naphtha with oxygen at elevated temperature and under partially reducing conditions. Naphtha is a liquid petroleum distillate fraction containing mostly paraffinic hydrocarbons having from 5 to 9 carbon atoms per molecule, and the usual composition of naphtha is described in detail in U.S. patent application Ser. No. 160,749 filed Dec. 20, 1961, now U.S. Patent No. 3,262,886. The reaction between the fluid hydrocarbon and oxygen produces a hot gas stream principally containing acetylene, solid carbon particles, carbon monoxide, hydrogen and water vapor.

2

Minor proportions of methane, carbon dioxide, aromatics and nitrogen may also be present. The hot gas stream is quenched to prevent further reaction with concomitant loss of acetylene, by projecting a liquid stream of heavy aromatic oil principally comprising naphthalene into the hot gas stream. It will be appreciated by those skilled in the art that homologs of naphthalene may also be effectively employed as the heavy aromatic quench oil. Thus, in the process description and claims infra, reference to naphthalene will be understood to encompass homologs of naphthalene as well as naphthalene itself, although naphthalene is the preferred heavy aromatic quench oil. A heavy aromatic oil such as naphthalene is the preferred quench agent, because the heavy aromatic oil is relatively resistant to thermal degradation due to contact with the hot gas stream, and also because the heavy aromatic oil is very effective in wetting and thereby entraining the solid carbon particles, so as to remove a major portion of the carbon particles from the gas stream during quenching. The heavy aromatic oil containing entrained carbon particles is separated from the quenched gas stream containing vaporized heavy aromatic oil, and the quenched gas stream is passed to further processing for purification and ultimate recovery of product acetylene.

The heavy aromatic quench oil containing entrained solid carbon particles is then cooled and recycled for further gas quenching. It is apparent that a buildup of solid carbon particles concentration in the quench oil will occur. Thus, it is a usual practice to treat a portion or all of the quench oil stream for removal of entrained solid carbon particles. In most instances, a minor portion of quench oil stream is withdrawn from the recycling quench oil, and is treated to remove solid carbon particles. The purified portion of quench oil is then added to the main stream of quench oil, and thus the solid carbon particles content of the total recycling quench oil is maintained at a suitable low level.

The solid carbon particles have been removed from the quench oil stream in the prior art by mechanical procedures such as filtration or centrifuging of the quench oil, to attain a solid-liquid separation. This procedure is not totally satisfactory, because of loss of quench oil which wets and remains with the solid carbon phase, and also because of mechanical difficulties in handling the relatively viscous slurry. Another prior art approach involves heating of the quench oil-carbon mixture, to vaporize and distill off the quench oil, which is subsequently condensed to liquid free of solid carbon particles, and then recycled. This sequence is also relatively undesirable, because in order to attain reasonably adequate vaporization and removal of quench oil from the mass of solid carbon particles, prolonged and intensive heating must be provided, which results in thermal degradation and decomposition of a substantial portion of the quench oil.

In the present invention, solid carbon particles are removed from the liquid stream of heavy aromatic quench oil by means of a novel procedure and method sequence. The heavy aromatic oil stream containing entrained solid carbon particles is mixed with a stream of light aromatic oil consisting of benzene or a benzene derivative, such as toluene or xylene, and having a low boiling point relative to the heavy aromatic oil. The median boiling point of the light aromatic oil should preferably be at least 50° C. below that of the heavy aromatic oil. Alternatively, a light paraffinic oil such as hexane or heptane may be employed instead of the light aromatic oil. Thus, a homogeneous mixture of heavy aromatic and light aromatic or paraffinic oils containing solid carbon particles is produced. It has been determined that this homogeneous mixture is readily separable into a solid carbon phase

free of aromatic oils and an aromatic or aromatic-paraffinic oils mixture free of solid carbon particles by the use of a conventional solids-liquid separation step, such as filtration or centrifuging. Centrifugal separation of the phases has been found to be preferable, in providing optimum separation without mechanical difficulties. The aromatic or aromatic-paraffinic oils mixture is then heated and distilled, to vaporize the light aromatic or paraffinic oil. The residual liquid aromatic oils phase consisting of heavy aromatic oil is then recycled.

In a preferred embodiment of the present invention, the main process gas stream containing residual heavy aromatic oil vapor is scrubbed and refluxed with light aromatic or paraffinic oil, to condense the heavy aromatic oil into a liquid phase with concomitant vaporization of the light aromatic or paraffinic oil into the gas stream. The liquid phase mixture of heavy aromatic oil and light aromatic or paraffinic oil produced after separation of solid carbon particles is added to the light aromatic or paraffinic oil during this scrubbing and reflux step, and the light aromatic or paraffinic oil component of the oils mixture is thus vaporized into the gas stream, while the heavy aromatic oil component of the aromatic oils mixture combines with the heavy aromatic oil liquid condensed from the gas stream.

The principal advantage of the procedure of the present invention is that solid carbon particles produced during acetylene manufacture are removed from the heavy aromatic quench oil without loss of quench oil due to thermal degradation or entrainment in the solid carbon particles. The requisite apparatus is simple and operates efficiently on the mixture of heavy aromatic oil and light aromatic or paraffinic oil plus entrained solid carbon particles, and the solid carbon is completely removed from the liquid phase. In addition, the use of light aromatic or paraffinic oil in a preferred embodiment of the present invention permits the removal of solid carbon particles by mixing a light aromatic or paraffinic oil with the heavy aromatic oil-carbon slurry to be integrated into the sequence for treating and purifying the process gas stream prior to acetylene recovery. Finally, the light aromatic or paraffinic oil component is readily separated from the liquid phase mixture of light aromatic or paraffinic and heavy aromatic oils by simple distillation of vaporization, and the uncontaminated heavy aromatic oil is thus readily recycled for further gas quenching without loss.

It is an object of the present invention to provide an improved procedure for acetylene production.

Another object is to provide an improved method for the removal of solid carbon particles from the quench oil in acetylene manufacture.

An additional object is to separate solid carbon particles from quench oil in acetylene manufacture without loss of quench oil.

A further object is to utilize a light aromatic or paraffinic oil in the separation of solid carbon particles from heavy aromatic quench oil employed in acetylene production.

Still another object is to integrate and combine the use of light aromatic or paraffinic oil in the separation of solid carbon particles from heavy aromatic quench oil utilized in acetylene manufacture, with the treatment of the process gas stream to remove residual heavy aromatic oil vapor.

Still a further object is to separate solid carbon particles from an acetylene-containing process gas stream in an improved manner.

An object is to minimize material handling requirements and simplify equipment required in the removal of solid carbon particles from the quench oil employed in acetylene manufacture.

These and other objects and advantages of the present invention will become evident from the description which follows. In the detailed process description infra, reference to light aromatic oil will be understood to encompass

pass the alternative usage of a light paraffinic oil such as hexane or heptane. Referring to the figure, a flowsheet showing the process and preferred embodiments of the invention is presented. The fluid paraffinic hydrocarbon feed stream 1 and oxygen stream 2 are passed into acetylene burner 3. Stream 1 may consist of any suitable fluid paraffinic hydrocarbon or hydrocarbon mixture, however the hydrocarbon in stream 1 will generally have from one to nine carbon atoms per molecule. As mentioned supra, methane or naphtha are preferred hydrocarbons for use as stream 1, and will usually be employed in commercial installations, although light paraffins such as propane or butane may also be employed. The mixing of streams 1 and 2 in unit 3 takes place in the upper part of unit 3, preferably by means of induction of stream 1 into stream 2 via a venturi mixing passage. The flame reaction of the mixed gas stream takes place at elevated temperature and under partially reducing conditions, below perforated refractory barrier 4. The resulting hot gas stream in unit 3 will typically be at a temperature in the range of 1000° C. to 1700° C., and will usually contain principally from about 5% to 12% acetylene by volume, together with solid carbon particles, carbon monoxide, hydrogen and water vapor.

The mixed and reacted process gas stream below perforated refractory barrier 4 is immediately quenched by contact with quench liquid stream 5 to a reduced temperature. Stream 5 consists of a liquid stream of heavy aromatic oil principally comprising naphthalene, and will typically have a median boiling point in the range of 210° C. to 300° C. Stream 5 will also usually contain entrained solid carbon particles, and wets and entrains additional solid carbon particles by contact with the hot gas stream. The warmed quench liquid is separated from the quenched gas stream in the lower part of unit 3, and collects in the bottom of unit 3. Warmed quench liquid stream 6 is withdrawn from the bottom of unit 3, and will usually contain from about 10% to 30% by weight of solid carbon particles. All of stream 6 may be processed for removal of solid carbon particles in accordance with the present invention, however stream 6 is preferably divided into a major portion stream 7 which is recycled for further gas quenching and a minor portion stream 8 which is usually less than about 5% of stream 6 and is processed for removal of solid-carbon particles in a manner to be described infra. Stream 7 is now combined with recycle stream 9, derived in a manner to be described infra, and the combined liquid quench oil stream 10 is passed through waste heat boiler 11 for cooling and heat recovery via steam generation. The cooled liquid quench oil stream 5 is now recycled for further gas quenching as described supra.

The quenched gas stream, now containing vaporized heavy aromatic oil and residual solid carbon particles, is withdrawn from unit 3 via stream 12, and is typically at a temperature in the range of 180° C. to 250° C. Stream 12 may be processed by a variety of techniques, to remove heavy aromatic oil vapor, residual solid carbon particles and other impurities, prior to recovery of product acetylene. However, in this preferred embodiment of the present invention, stream 12 is passed into the lower part of gas scrubber 13 below gas-liquid contact trays 14. Scrubbing liquid stream 15 consisting of a heavy aromatic oil comparable to stream 5 described supra, is admitted into the upper part of scrubber 13 above trays 14. Stream 15 differs essentially from stream 5 in composition only in that the proportion of entrained solid carbon particles in stream 15 is much lower than in stream 5. The scrubbing of stream 12 in unit 13 results in the removal of substantially all of the residual entrained solid carbon particles from the gas phase into the scrubbing liquid. In addition, the gas stream is cooled in unit 13 and most of the heavy aromatic oil vapor is condensed into the liquid phase.

The resulting warmed heavy aromatic oil scrub liquid

is withdrawn from unit 13 via stream 16, and contains an increment of heavy aromatic oil derived from the quench oil vapor in stream 12 as well as entrained solid carbon particles derived from stream 12. Stream 16 is now divided into stream 9 which is recycled to the quench step as described supra, and recycle scrub liquid stream 17. The recycle stream 17 is combined with recycle heavy aromatic oil stream 18 derived in a manner to be described infra, and the combined liquid heavy aromatic oil stream 19 is passed through waste heat boiler 20 for cooling and heat recovery via steam generation. The cooled liquid scrub oil stream 15 is now recycled for further gas scrubbing and cooling as described supra.

The scrubbed and cooled gas stream now leaves unit 13 via stream 21, which is typically at a temperature in the range of 130° C. to 180° C. and contains residual heavy aromatic oil vapor together with a very minor proportion of entrained solid carbon particles. Stream 21 is now passed into the lower part of scrubbing and gas reflux unit 22 below lower packed section 23. A final removal of solid carbon particles and condensation of residual heavy aromatic oil vapor from the gas stream into a liquid phase is attained in unit 22, together with concomitant vaporization of light aromatic oil into the gas stream, as described infra. Thus, the gas stream 21 rises within unit 22 and passes through packed section 23, which is any conventional means for gas-liquid contact such as a packed bed provided with Raschig rings. A scrubbing liquid stream 24 is admitted into unit 22 above bed 23 and is dispersed into the packing of bed 23, thus flowing downwards and scrubbing the rising gas stream. Stream 24 consists of heavy aromatic oil of a composition similar to stream 5 described supra, and an additional amount of cool heavy aromatic oil flows downward into packed bed 23 from gas reflux bubble cap trays section 25 in the upper part of unit 22, to be described infra. Thus, the rising gas stream is scrubbed and slightly further cooled in bed 23, by contact with the downflowing liquid phase. Removal of residual entrained solid carbon particles from the gas stream and condensation of heavy aromatic oil vapor thus takes place in bed 23. The scrub liquid from bed 23 is collected in the bottom of unit 22 and withdrawn as stream 26. Stream 26 is divided into recycle stream 18 which is added to stream 17 as described supra, and stream 27 which is recycled for further gas scrubbing in bed 23. Stream 27 is combined with make-up heavy aromatic oil stream 28 to form stream 24. Stream 28 is of a composition similar to stream 5 described supra, and is added to compensate for process losses in the system.

The rising gas stream in unit 22 now rises from bed 23 and flows through gas reflux section 25, which preferably consists of a plurality of bubble cap traps. A liquid reflux stream 29 is passed into unit 22 above section 25. Stream 29 consists of a light aromatic oil such as benzene or a benzene derivative such as xylene or toluene or a mixture of these compounds and usually will have a median boiling point generally in the range of 80° C. to 170° C. Stream 29 preferably consists primarily of xylene. In any case, the median boiling point of stream 29 is below that of stream 5 and preferably at least 50° C. lower than that of stream 5. As mentioned supra, stream 29 may alternatively consist of a light paraffinic oil such as hexane or heptane. Thus, reference to a light aromatic oil encompasses usage of light paraffinic oil. Stream 29 flows downwards through bubble cap plates 25, in reflux contact with the rising gas stream, and is substantially completely vaporized into the rising gas stream, thus serving to cool the gas stream and condense residual heavy aromatic oil vapor to liquid, which flows downward from section 25 and into bed 23 as described supra.

A liquid stream 30 consisting of a mixture of light and heavy aromatic oils and derived in a manner to be described infra is preferably also passed into unit 22, and onto an intermediate plate 25 having a liquid phase

composition comparable to that of stream 30 itself. In essence then, stream 30 is added to the liquid stream of light aromatic oil during the scrubbing and reflux of the gas stream with light aromatic oil. The light aromatic oil component of stream 30 thus is vaporized into the rising gas stream, while the heavy aromatic oil component of stream 30 flows downward through trays 25 in the liquid state and thence forms a component of the liquid heavy aromatic oil flowing downward through bed 23.

The gas stream is thus further cooled in the reflux section 25, with concomitant total vaporization of stream 29 into the gas stream and complete condensation of heavy aromatic oil vapor from the gas stream into the liquid phase. The resulting cooled gas stream is withdrawn from unit 22 via stream 31, typically at a temperature in the range of 70° C. to 130° C., and is now processed to remove light aromatic oil vapor and also a major portion of its water vapor content by condensation to the liquid phase. Thus, stream 31 is passed into packed scrubbing tower 32 below packed section 33, which is any suitable means for gas-liquid contact such as a bed of Raschig rings packing. A liquid stream 34 consisting of cold scrubbing water is admitted into unit 32 above bed 33, and flows downward through bed 33 countercurrent to the rising gas stream, thus serving to condense all of the light aromatic oil vapor and a major portion of the water vapor from the gas stream into the liquid phase. The resulting cold gas stream, now at a temperature typically in the range of 30° C. to 70° C., is discharged from unit 32 via stream 35, and is passed to suitable processing for the recovery of acetylene in a conventional manner. This procedure, not shown, will typically include compression of the gas stream 35, followed by scrubbing with a selective liquid solvent for acetylene. The liquid solvent containing absorbed acetylene is then heated to evolve a gaseous stream of pure product acetylene.

Returning to unit 32, the water scrub liquid flows downward from packed section 33 and is withdrawn from the bottom of unit 32 as liquid stream 36, which contains separate and immiscible water and organic liquid phases. The organic liquid phase in stream 36 consists of light aromatic oil condensed from stream 31. Stream 36 is now divided into separate streams of water and light aromatic oil by conventional procedure such as decanting, thus stream 36 is preferably passed into decanter 37 where stream 36 divides into separate light aromatic oil layer 38 which flows over baffle 39, and lower water layer 40. Water is withdrawn from layer 40 via stream 41, which is divided into water recycle stream 42 and excess water stream 43 which is discarded. Stream 43 corresponds to the water vapor condensed from stream 31 in unit 32. Water recycle stream 42 is cooled in cooler 44 and recycled via stream 34 for further gas scrubbing.

The light aromatic oil liquid is withdrawn from decanter 37 as stream 45, which is divided into stream 29 and stream 46. Stream 29 is recycled for gas reflux and cooling as described supra, while stream 46 is now employed in the removal of solid carbon particles from the heavy aromatic quench oil. Thus, light aromatic oil stream 46 is now combined with heavy aromatic oil stream 8 containing entrained solid carbon particles in mixer 47, which produces a homogeneous liquid mixture of light and heavy aromatic oils containing solid carbon particles. The liquid mixture is discharged from mixer 47 as stream 48, which is now readily separable into a solid carbon phase substantially free of aromatic oils and a liquid aromatic oils mixture substantially free of solid carbon in conventional solid-liquid separation means such as a filter apparatus or a centrifugal separator. Centrifugal separation is preferable in providing more rapid and complete separation in simpler apparatus. Thus, stream 48 is passed into centrifuge 49, which discharges a solid carbon phase stream 50 substantially free of aromatic oils and a liquid stream 30 consisting of a mixture of light and heavy aromatic oils substantially free of solid carbon. Stream 30 is

now recycled to the process as described supra, while stream 50 may be discarded or utilized as fuel or for other suitable purposes.

Numerous alternatives within the scope of the present invention will occur to those skilled in the art. In this respect, it is to be understood that the process ranges of operating variables, such as temperature ranges enumerated supra, constitute merely a preferred embodiment of the procedure of the present invention and should not be construed to modify or restrict the inventive concepts of the present invention, since the procedure of the present invention is also operable outside of these process ranges and may be followed outside of these process ranges in suitable instances.

As mentioned supra, stream 12 may be processed in a variety of ways to remove vaporized heavy aromatic oil, entrained solid particles and other impurities, prior to the recovery of product acetylene. However, the processing enumerated supra wherein a light aromatic oil is employed as a reflux stream to cool and scrub the quenched gas stream thereby condensing heavy aromatic oil vapor to liquid and producing a gas stream containing vaporized light aromatic oil which is subsequently condensed by cold water scrub, constitutes a preferred embodiment of the present invention. In addition, the process concept in which stream 30, consisting of a mixture of light and heavy aromatic oils, is added to the liquid light aromatic oil phase on bubble cap tray 25 in unit 22 during gas reflux and scrubbing, in order to separate stream 30 into vaporized light aromatic oil component and liquid heavy aromatic oil component which is recycled, constitutes a novel and preferred process sequence and a new combination of process steps within the scope of the present invention.

The alternative of separately heating stream 30 in a special separate distillation column, to vaporize and separate the light aromatic oil component from aromatic oils mixture 30, leaving a liquid heavy aromatic oil component which is recycled to gas quenching, with subsequent condensation of the vaporized light aromatic oil component and recycle to mixer 47, would also be employed when stream 12 is processed by means other than as described supra to recover product acetylene, and light aromatic oil is not employed for gas scrubbing and reflux.

An example of an industrial application of the present invention will now be described.

Example

- 15 A fluid hydrocarbon feed stream 1 consisting of a total of 62,040 lbs./hr. of petroleum naphtha having an average molecular weight of 84 was reacted with a total of 63,700 lbs./hr. of 98% oxygen to produce an acetylene-containing gas in accordance with the present invention. The reaction actually took place in a total of six parallel acetylene burners, with the respective feed streams being divided into six portions, however flow quantities in the material balance infra will be expressed as overall totals for the entire facility. The final product gas stream 35 20 contained 8.82% acetylene by volume, together with 35.27% carbon monoxide, 41.14% hydrogen, 3.85% water vapor, 3.98% methane, 3.70% carbon dioxide, and minor proportions of other organics and inerts. Stream 35 25 was produced at a temperature of 29.4° C. with a total production flow rate of 112,890 lbs./hr.

Following is a tabulation of the temperature and flow rate of major process streams in the facility. All flow rates are expressed in lbs./hr. of the individual components present in the flow stream.

Stream Number	Temp., °C.	Composition of Stream, lbs./hr.				
		Dry Gas	Naphthalene	Xylene	Carbon	Water
12	190	100,300	520,000	-----	228	21,700
21	152	100,300	146,200	-----	-----	21,700
31	90	100,300	-----	186,420	-----	21,700
6	185	-----	6,570,000	-----	1,641,000	-----
8	185	-----	18,410	-----	4,600	-----
5	173	-----	6,560,000	-----	1,638,000	-----
9	189	-----	539,500	-----	228	-----
19	185	-----	1,853,000	-----	715	-----
15	150	-----	1,853,000	-----	715	-----
17	189	-----	1,688,000	-----	715	-----
26	149	-----	2,464,810	-----	-----	-----
18	149	-----	166,100	-----	-----	-----

28	45	-----	-----	1,440	-----	-----
45	50	-----	-----	186,420	-----	-----
46	50	-----	-----	36,820	-----	-----
36	51	-----	-----	189,580	-----	1,152,000
34	26.7	-----	-----	3,160	-----	1,133,000
43	51	-----	-----	133	-----	35,890
30	75	-----	18,410	36,820	4,600	-----
50	75	-----	-----	-----	-----	-----

In some cases, it may prove relatively less desirable to introduce stream 30 into unit 22 for separation into light and heavy aromatic oil phases. This would be especially true when stream 30 contains a relatively high proportion of heavy aromatic oil, because a complete removal of heavy aromatic oil vapor from the gas stream in trays section 25 may then be difficult to attain. In this case, stream 30 may be separately heated in a special separate distillation column, to vaporize and separate the light aromatic oil component from the aromatic oils mixture 30. The vaporized light aromatic oil component would then be separately condensed and directly recycled to mixer 47, and the residual heavy aromatic oil component of stream 30 would be recycled in stream 28 or directly recycled to quenching as a component of stream 5. In this case, stream 45 would be recycled completely as stream 29. This alternative would be particularly desirable if the light aromatic oil employed in mixer 47 for mixing with stream 8 and subsequent separation of solid carbon particles free of aromatic oils is of different composition from the light aromatic oil employed for gas reflux and scrubbing in unit 22 as stream 29, which could be possible in suitable instances.

In the process sequence according to the material balance supra, stream 9 was recycled directly into the lower part of unit 3. Hence the flow rates for stream 6 include the added components derived from stream 9. In addition, a small amount of vaporized xylene was present in stream 35. This xylene content was recovered during the subsequent processing of stream 35 to recover product acetylene, and was recycled to unit 37. A very minor quantity of residual xylene was present in stream 50 and constituted a process loss, and a small amount of carbon was present in stream 30. However, for all practical purposes, stream 50 was substantially free of naphthalene and xylene, and stream 30 was substantially free of carbon. Finally, in actual operation of the process sequence, two centrifuges 49 were provided. Stream 46 was divided into two equal portions. A first portion of stream 46 was added to stream 8 and the mixture was passed to the first centrifuge. The resulting solids component was mixed with the second portion of stream 46 and passed to the second centrifuge. The resulting solids discharge constituted stream 50, while the liquid discharge from the second centrifuge was also added to stream 8 prior to the first centrifuge.

I claim:

1. In a process for the production of acetylene wherein a fluid paraffinic hydrocarbon and oxygen are reacted at elevated temperature to produce a hot gas stream principally containing acetylene, solid carbon particles, carbon monoxide, hydrogen and water vapor, said hot gas stream is quenched to reduced temperature by contact with a first liquid stream of heavy aromatic oil having an elevated boiling point and principally comprising naphthalene, said first heavy aromatic oil stream containing entrained solid carbon particles is separated from the quenched gas stream containing vaporized heavy aromatic oil and is cooled and recycled for further gas quenching, said quenched gas stream is quenched with a second liquid stream of heavy aromatic oil principally comprising naphthalene, whereby said gas stream is cooled and residual entrained carbon and vaporized heavy aromatic oil are removed from said gas stream, the cooled gas stream is scrubbed and refluxed with a liquid stream of light aromatic oil selected from the group consisting of benzene and benzene derivatives, and having a low boiling point relative to the boiling point of said heavy aromatic oil, whereby said gas stream is further cooled and residual heavy aromatic oil vapor is condensed from said gas stream, said condensed liquid heavy aromatic oil is recycled for further scrubbing of the quenched gas stream, said light aromatic oil being vaporized into said gas stream, the resulting gas stream containing vaporized light aromatic oil is scrubbed with liquid water whereby said vaporized light aromatic oil and water vapor are condensed from said gas stream and a liquid stream containing a light aromatic oil phase and a separate water phase is produced, said condensed light aromatic oil phase is separated from the liquid water phase, the separated liquid light aromatic oil is recycled for further gas scrubbing and reflux, and the residual cold gas stream is processed to recover product acetylene, the improved method of separating entrained solid carbon particles from said first heavy aromatic oil stream which comprises mixing at least a portion of said first heavy aromatic oil stream containing solid carbon particles with a portion of said separated liquid light aromatic oil, separating the resulting liquid oils mixture containing solid carbon particles into a solid carbon phase substantially free of oils and a liquid oils phase substantially free of solid carbon, and vaporizing light aromatic oil from said liquid oils phase by adding said liquid oils phase comprising a mixture of light aromatic and heavy aromatic oils substantially free of solid carbon particles to said gas stream during said scrubbing and reflux of said gas stream with said light aromatic oil, whereby the light aromatic oil component of said liquid oils phase is vaporized into said gas stream and the heavy aromatic oil component of said liquid oils phase is recovered as a component of the residual heavy aromatic oil liquid condensed from said gas stream.

2. The process of claim 1, in which said fluid paraffinic hydrocarbon consists of naphtha.

3. The process of claim 1, in which said fluid paraffinic hydrocarbon is methane.

4. The process of claim 1, in which said light aromatic oil is xylene.

5. The process of claim 1, in which said liquid oils mixture containing solid carbon particles is separated into a solid carbon phase and a liquid oils phase by passing said oils mixture through centrifugal means for solid-liquid separation.

6. A process for the production of acetylene from a hydrocarbon and separation of solid carbon particles therefrom which comprises reacting a fluid paraffinic hydrocarbon having from one to nine carbon atoms per molecule with oxygen at elevated temperature to produce a hot gas stream principally containing acetylene, solid carbon particles, carbon monoxide, hydrogen and water vapor, quenching said hot gas stream to reduced temperature by contact with a liquid stream of heavy aromatic

oil having an elevated boiling point and principally comprising naphthalene, separating said heavy aromatic oil stream containing entrained solid carbon particles from the quenched gas stream containing vaporized heavy aromatic oil, dividing said heavy aromatic oil stream containing entrained solid carbon particles into a major portion and a minor portion, cooling and recycling said major portion of said heavy aromatic oil stream for further gas quenching, cooling and scrubbing said quenched gas stream by contact with a liquid reflux stream comprising a first liquid stream of light aromatic oil, said first light aromatic oil stream comprising a light aromatic oil selected from the group consisting of benzene and benzene derivatives and having a low boiling point relative to the boiling point of said heavy aromatic oil, whereby heavy aromatic oil vapor and residual entrained carbon are removed from said quenched gas stream in a liquid heavy aromatic oil condensate and said first light aromatic oil stream is vaporized into the cooled gas stream, processing the cooled gas stream to recover acetylene product, mixing said minor portion of said heavy aromatic oil stream containing entrained solid carbon particles with a second liquid stream comprising a light aromatic oil selected from the group consisting of benzene and benzene derivatives and having a low boiling point relative to the boiling point of said heavy aromatic oil, separating the resulting aromatic oils mixture containing solid carbon particles into a solid carbon phase substantially free of aromatic oils and a liquid oils phase, vaporizing light aromatic oil from said liquid oils phase by adding said liquid oils phase comprising a mixture of light aromatic and heavy aromatic oils substantially free of solid carbon particles to said gas stream during said scrubbing and reflux of said gas stream with said light aromatic oil, whereby the light aromatic oil component of said liquid oils phase is vaporized into said gas stream and the heavy aromatic oil component of said liquid oils phase is recovered as a component of said liquid heavy aromatic oil comprising heavy aromatic oil to said quenching of said hot gas stream.

7. The process of claim 6, in which said light aromatic oil is xylene.

8. A process for the production of acetylene from a hydrocarbon and separation of solid carbon particles therefrom which comprises reacting a fluid paraffinic hydrocarbon having from one to nine carbon atoms per molecule with oxygen at elevated temperature to produce a hot gas stream principally containing acetylene, solid carbon particles, carbon monoxide, hydrogen and water vapor, quenching said hot gas stream to reduced temperature by contact with a first liquid stream of heavy aromatic oil having an elevated boiling point and principally comprising naphthalene, separating said first heavy aromatic oil stream containing entrained solid carbon particles from the quenched gas stream containing vaporized heavy aromatic oil, dividing said first heavy aromatic oil stream containing entrained solid carbon particles into a major portion and a minor portion, cooling and recycling said major portion of said first heavy aromatic oil stream for further gas quenching, scrubbing said quenched gas stream with a second liquid stream of heavy aromatic oil principally comprising naphthalene, whereby said gas stream is cooled and residual entrained carbon and vaporized heavy aromatic oil are removed from said gas stream, further cooling and scrubbing the cooled gas stream to condense and remove residual heavy aromatic oil vapor by contacting said cooled gas stream with a liquid reflux stream comprising a first liquid stream of light aromatic oil, said first light aromatic oil stream comprising a light aromatic oil selected from the group consisting of benzene and benzene derivatives and having a low boiling point relative to the boiling point of said heavy aromatic oil, whereby heavy aromatic oil vapor and residual entrained carbon are removed from said cooled gas stream in a

liquid heavy aromatic oil condensate and said first light aromatic oil stream is vaporized into the cooled gas stream, processing the cooled gas stream to recover acetylene product, mixing said minor portion of said first heavy aromatic oil stream containing entrained solid carbon particles with a second liquid stream comprising a light aromatic oil selected from the group consisting of benzene and benzene derivatives and having a low boiling point relative to the boiling point of said first heavy aromatic oil, separating the resulting aromatic oils mixture containing solid carbon particles into a solid carbon phase substantially free of aromatic oils and a liquid oils phase, vaporizing light aromatic oil from said liquid oils phase by adding said liquid oils phase comprising a mixture of heavy and light aromatic oils to said cooled gas stream during said scrubbing and reflux of said gas stream with said first stream of light aromatic oil, whereby the light aromatic oil component of said liquid oils phase is vaporized into said gas stream and the heavy aromatic oil component of said liquid oils phase is recovered as a liquid component of said liquid heavy aromatic oil condensate, and recycling said condensed liquid heavy aromatic oil comprising heavy aromatic oil by adding said condensed liquid aromatic oil to said second heavy aromatic oil stream.

9. A process for the production of acetylene from a hydrocarbon and separation of solid carbon particles therefrom which comprises reacting a fluid paraffinic hydrocarbon having from one to nine carbon atoms per molecule with oxygen at elevated temperature to produce a hot gas stream principally containing acetylene, solid carbon particles, carbon monoxide, hydrogen and water vapor, quenching said hot gas stream to reduced temperature by contact with a first liquid stream of heavy aromatic oil having an elevated boiling point and principally comprising naphthalene, separating said first heavy aromatic oil stream containing entrained solid carbon particles from the quenched gas stream containing vaporized heavy aromatic oil, dividing said first heavy aromatic oil stream containing entrained solid carbon particles into a major portion and a minor portion, cooling and recycling said major portion of said first heavy aromatic oil stream for further gas quenching, scrubbing said quenched gas stream with a second liquid stream of heavy aromatic oil principally comprising naphthalene, whereby said gas stream is cooled and residual entrained carbon and vaporized heavy aromatic oil are removed from said gas stream, scrubbing and refluxing the cooled gas stream with a liquid stream of light aromatic oil selected from the group consisting of benzene and benzene derivatives and having a low boiling point relative to the boiling point of said first heavy aromatic oil, whereby said gas stream is further cooled, said light aromatic oil is vaporized into said gas stream, and residual heavy aromatic oil vapor is condensed from said gas stream, recycling said condensed liquid heavy aromatic oil for further scrubbing of the quenched gas stream by adding said condensed liquid heavy aromatic oil to said second liquid stream of heavy aromatic oil, scrubbing the further cooled gas stream containing vaporized light aromatic oil with liquid water, whereby said gas stream is cooled and said vaporized light aromatic oil and water vapor are condensed from said gas stream into a liquid stream containing a light aromatic oil phase and a separate water phase, separating said condensed light aromatic oil phase from the liquid water phase, dividing said light aromatic oil phase into a first portion and a second portion, recycling said first portion of said light aromatic oil phase as said liquid stream of light aromatic oil, processing the residual cold gas stream to recover product acetylene, mixing said second portion of said light aromatic oil phase with said minor portion of said first heavy aromatic oil stream containing entrained solid carbon particles, separating the resulting liquid aromatic oils mixture containing solid carbon particles into a solid carbon phase substantially free of aromatic oils and

a liquid aromatic oils phase substantially free of solid carbon, and vaporizing light aromatic oil from said liquid aromatic oils phase by adding said liquid aromatic oils phase to said gas stream during said scrubbing and reflux of said cooled gas stream with said liquid stream of light aromatic oil, whereby the light aromatic oil component of said liquid oils phase is vaporized into said gas stream and the heavy aromatic oil component of said liquid oils phase is recovered as a component of said condensed liquid heavy aromatic oil.

10. A process for the production of acetylene from a hydrocarbon and separation of solid carbon particles therefrom which comprises reacting a fluid paraffinic hydrocarbon having from one to nine carbon atoms per molecule with oxygen to produce a gas stream at a temperature in the range of 1000° C. to 1700° C., said gas stream principally containing from about 5% to 12% acetylene by volume together with solid carbon particles, carbon monoxide, hydrogen and water vapor, quenching said gas stream to a temperature in the range of 180° C. to 250° C. by contact with a first liquid stream of heavy aromatic oil having a median boiling point in the range of 210° C. to 300° C. and principally comprising naphthalene, separating said first heavy aromatic oil stream containing from about 10% to 30% by weight of entrained solid carbon particles from the quenched gas stream containing vaporized heavy aromatic oil, dividing said first heavy aromatic oil stream containing entrained solid carbon particles into a major portion and a minor portion, said minor portion being less than 5% of the total stream, cooling and recycling said major portion of said first heavy aromatic oil stream for further gas quenching, scrubbing said quenched gas stream with a second liquid stream of heavy aromatic oil having a median boiling point in the range of 210° C. to 300° C. and principally comprising naphthalene, whereby said gas stream is cooled to a reduced temperature in the range of 130° C. to 180° C. and residual entrained carbon and vaporized heavy aromatic oil are removed from said gas stream, scrubbing and refluxing the cooled gas stream with a liquid stream of light aromatic oil selected from the group consisting of benzene and benzene derivatives and having a median boiling point in the range of 80° C. to 170° C., whereby said gas stream is further cooled to a temperature in the range of 70° C. to 130° C., said light aromatic oil is vaporized into said gas stream, and residual heavy aromatic oil vapor is condensed from said gas stream, recycling said condensed liquid heavy aromatic oil for further scrubbing of the quenched gas stream by adding said condensed liquid heavy aromatic oil to said second liquid stream of heavy aromatic oil, scrubbing the further cooled gas stream containing vaporized light aromatic oil with liquid water, whereby said gas stream is cooled to a temperature in the range of 30° C. to 70° C., and said vaporized light aromatic oil and water vapor are condensed from said gas stream into a liquid stream containing a light aromatic oil phase and a separate water phase, separating said condensed light aromatic oil phase from the liquid water phase, dividing said light aromatic oil phase into a first portion and a second portion, recycling said first portion of said light aromatic oil phase as said liquid stream of light aromatic oil, processing the residual cold gas stream to recover product acetylene, mixing said second portion of said light aromatic oil phase with said minor portion of said first heavy aromatic oil stream containing entrained solid carbon particles, separating the resulting liquid aromatic oils mixture containing solid carbon particles into a solid carbon phase substantially free of aromatic oils and a liquid aromatic oils phase substantially free of solid carbon particles, and vaporizing light aromatic oil from said liquid aromatic oils phase at a temperature in the range of 70° C. to 130° C., by adding said aromatic oils phase to said gas stream during said scrubbing and reflux of said cooled gas stream with said liquid stream of light aromatic oil, whereby the light aromatic oil component of said

13

liquid oils phase is vaporized into said gas stream and the heavy aromatic oil component of said liquid oils phase is recovered as a component of said condensed liquid heavy aromatic oil.

11. In a process for the production of acetylene in which a fluid paraffinic hydrocarbon and oxygen are reacted at elevated temperature to produce a hot gas stream principally containing acetylene, solid carbon particles, carbon monoxide, hydrogen and water vapor, said hot gas stream is quenched to reduced temperature by contact with a liquid stream of heavy aromatic oil having an elevated boiling point and principally comprising naphthalene, said heavy aromatic oil stream containing entrained solid carbon particles is separated from the quenched gas stream containing vaporized heavy aromatic oil, the separated heavy aromatic oil stream is cooled and recycled for further gas quenching, said gas stream is scrubbed and refluxed in gas-liquid contact means with a liquid stream of light aromatic oil selected from the group consisting of benzene and benzene derivatives, said light aromatic oil having a low boiling point relative to the boiling point of said gas stream, and the residual cold gas stream is cooled, heavy aromatic oil vapor is condensed from said gas stream, and said light aromatic oil is vaporized into said gas stream, the condensed liquid heavy aromatic oil is recycled and combined with said separated heavy aromatic oil stream, the resulting gas stream containing vaporized light aromatic oil is further cooled to condense liquid light aromatic oil, said condensed liquid light aromatic oil is recycled for further scrubbing and refluxing of said gas stream, and the residual cold gas stream is processed to recover product acetylene, the improved method of separating solid carbon particles from said heavy aromatic quench oil stream which comprises

(a) mixing at least a portion of said heavy aromatic quench oil stream containing solid carbon particles

14

with a portion of said condensed liquid light aromatic oil,

(b) separating the resulting liquid oils mixture containing solid carbon particles into a solid carbon phase substantially free of oils and a liquid oils phase substantially free of solid carbon, and

(c) adding said liquid oils phase produced by step (b) into said gas-liquid contact means during said scrubbing and refluxing of said gas stream, whereby light aromatic oil is vaporized from said liquid oils phase into said gas stream, and the heavy aromatic quench oil component of said liquid oils phase combines with said condensed liquid heavy aromatic oil and is thereby recycled for further gas quenching.

12. The process of claim 11, in which said light aromatic oil is xylene.

13. The process of claim 11, in which said fluid paraffinic hydrocarbon consists of naphtha.

14. The process of claim 11, in which said fluid paraffinic hydrocarbon is methane.

15. The process of claim 8, in which said light aromatic oil is xylene.

16. The process of claim 9, in which said light aromatic oil is xylene.

17. The process of claim 10, in which said light aromatic oil is xylene.

UNITED STATES PATENT OFFICE
CERTIFICATE OF CORRECTION

Patent No. 3,392,210

July 9, 1968

Robert S. Puistonen

It is certified that error appears in the above identified patent and that said Letters Patent are hereby corrected as shown below:

Column 9, lines 35 and 42, "tight", each occurrence, should read -- light --. Column 13, line 22, "gas stream, and the residual cold" should read -- heavy aromatic oil, whereby said --.

Signed and sealed this 2nd day of December 1969.
